(57) **CLAIM**

The ornamental design for the drink bottle as shown.

DESCRIPTION

FIG. 1 is a front perspective view of a drink bottle in accordance with the invention;

FIG. 2 is a rear perspective view thereof;

FIG. 3 is a front view thereof;

FIG. 4 is a rear view thereof;

FIG. 5 is a side view thereof;

FIG. 6 is an opposing side view thereof;

FIG. 7 is a top view thereof; and,

FIG. 8 is a bottom view thereof.

1 Claim, 7 Drawing Sheets
